UNITED STATES PATENT OFFICE.

JOSHUA BROOKS, OF BOSTON, MASSACHUSETTS.

DESIGN FOR AN ADVERTISING PRINT.

Specification forming part of Design No. 5,068, dated July 4, 1871.

To all whom it may concern:

Be it known that I, JOSHUA BROOKS, of Boston, in the county of Suffolk and State of Massachusetts, have invented certain Improvements in Design for Advertising Medium, of which the following is a specification:

Figure 1 represents one side of my design, and Fig. 2 the reverse of the same.

This invention relates to a design for an advertising medium; said design consisting of a bond with a coupon attached thereto as an advertising medium, as will hereafter more fully appear.

In the drawings, *a* represents a bond, to which is attached a coupon, *b*. The face of the bond *a* is provided with a space, *c*, in which an advertisement can be inserted. The face and back of the bond and coupon are provided with rectangular borders of ornamental lathe-work, and upon the face of the bond, within this border at each corner, is a picture—that at the upper left-hand corner representing a female figure holding a balance and leaning on a shield. In the upper right-hand corner is a view of a male figure seated by a body of water. At the lower right-hand corner is a representation of two horses drawing a plow. The last picture on the face is in the lower left-hand corner, and represents a steamboat.

Above the space *c*, in bold German characters, is the title, "Mercantile Advertising Bond," and at the right and left of said space are the words, "Our goods are sold to the holder of this bond at our regular cash prices." On the back of the bond, and occupying corresponding positions to those on the face, are four pictures, representing, respectively, a railroad train, an express-wagon, the American eagle, and a fountain. At the center is an elliptical inclosure containing certain printed matter, the most prominent words of which are as follows: "The person holding this mercantile advertising bond will receive a valuable present," &c.

By this means advertisements can be presented to the public in a novel and attractive form.

Having thus fully described my invention, what I claim as new, and desire to secure by Letters Patent, is—

The design for an advertising medium, substantially as shown and described.

In testimony whereof I have signed my name to this specification in the presence of two subscribing witnesses.
